UNITED STATES PATENT OFFICE.

SIDNEY M. BOOKMAN, OF NEW YORK, N. Y.

REPEATING DEVICE FOR PHONOGRAPHIC RECORDS.

Application filed October 25, 1922. Serial No. 596,813.

This invention relates to a repeating device for phonographic records. In developing this invention, it was my object to provide a simple, durable, economically manufactured device to be applied to phonograph records for causing the repetition of selections thereon; and especially the provision of a device which could readily be adapted for different sizes and kinds of records and which would not stick when the needle was passing over it.

Another object was to provide a repeater device which was light in construction, to impede the speed of the record as little as possible and yet which when operated would not be defective.

A further object of the invention relates to the provision of a repeating plate which bears effectively on a record but only on those portions not covered by the grooves with the exception of a brush portion of the plate which is provided to clean the grooves while the record is moving.

A still further object resides in the provision of a plate provided with means to more effectively guide the needle into the outermost groove of the record without any liability of the needle running off the record or running across the grooves to produce a scratch.

Another object resides in the provision of a repeater plate which along a certain part is sufficiently flexible when subjected to the weight of the needle and the tone arm to be depressed against the record temporarily, whereby the friction between the plate and the record is increased temporarily to insure the positive movement of the plate with the record, the flexibility of the plate, however, insuring the immediate removal of the contact and friction between the plate and the record when the weight of the needle and the tone arm is removed from the plate.

The invention is illustrated in the drawings, of which—

Figure 1 is a plan view of the preferred form of my invention.

Fig. 2 is a section taken on the line 2—2 of Fig. 1.

Fig. 3 is an inverted plan view of the device.

Fig. 4 is a section taken on the line 4—4 of Fig. 1.

Fig. 5 is a section taken on the line 5—5 of Fig. 1.

Fig. 6 is a section taken on the line 6—6 of Fig. 1.

Fig. 7 is a section similar to that shown in Fig. 6 showing the parts in position when the needle is riding on the device.

Fig. 8 is a partial plan view of a modified form of the repeater.

It is, of course, understood that the forms of the invention shown in the drawings are preferred forms and that the construction and arrangement of the parts and the character of the material used can be varied within reasonable limits without departing from the spirit of the invention.

The invention concerns a flat plate, preferably of some light material such as rubber, amber or celluloid, which is to be disposed on the record and provided with bearing portions to rest on the record. These bearing portions, however, are formed, preferably, on the plate by molding or shaping it so that the bearing portions bear on the level portion of the record and the outer edges or margins of the record, namely, those portions which do not have the phonographic grooves therein, so that the weight of the plate is not borne by the grooves to injure them in any way. Furthermore, this plate is provided with a cam slot adapted to swing the needle from the center of the record to the outermost groove, this slot being provided with the needle bearing surface. The outer forward end of the plate is provided with a needle guiding edge, so that the needle is positively and accurately fed into the exact part of the record desired without any possibility of its having lateral movement to jump from one groove to another or off the record entirely whereby the grooves would be scratched.

Preferably the part of the record upon which this guide member or edge directs the needle is the outer edge or portion which is not provided with grooves, so that as the needle drops off the flexible portion it will drop on to an ungrooved part inwardly, so that the force of this impact will be taken by a part of the record the injury of which will not be particularly harmful. The outer end of the guiding edge will then steer the record into the outermost groove.

The invention, furthermore, contemplates the provision of a repeater plate in which the only portion of the plate which firmly bears on the grooves is the brush portion which tends to clean the grooves immediately ahead of the needle, whereby dust and dirt will be removed therefrom to eliminate all objectionable discordant noises produced

by the presence of the dust in the grooves.

The invention, further, contemplates the formation and molding of the plate with reinforcing or stiffening construction on both 5 sides of the cam slot and the needle bearing surface disposed therein, so that the needle bearing surface, although preferably formed of the same material of which the plate is made and integral therewith, is, nevertheless, 10 relatively flexible compared to the other portions of the plate, whereby when the needle bears on this surface it will tend to be depressed and the underside of this surface is provided with some friction material, such as 15 felt or plush, to temporarily bear against the record and insure the proper friction between the plate and the record.

The invention also includes the provision of a plurality of holes in the central hub 20 of the flat plate whereby these may as desired be disposed over the rotary pin of the phonograph to adapt the plate for differently sized records.

A further feature of the invention relates 25 to the combination of the cleaning brush with the adjustable needle bar whereby the motion of the record to be played before the plate is released to repeat can be adjusted as desired.

In applying these ideas in a practical 30 way, I have developed the form shown in Figs. 1, 2 and 3, and this comprises a curved plate 1 having depressed portions such as 2 formed therein to strengthen the plate. 35 This plate is preferably pressed or molded into shape and is provided with a curved cam groove 3 extending from the point near the central portion of the plate, where the groove is broadest, to a point near the end 40 of the plate in line with the outermost groove of the record on which the plate is disposed. At this point the groove 3 is narrow, being scarcely wider than the end of the needle running therein. Disposed in the latter portion of the groove, and adapted to receive the needle as it travels in the groove, 45 is a surface 4 which is preferably made of the same material of which the plate is made and may be formed integrally therewith. This surface 4, because the plate on either side thereof has been reinforced in the manner above described, is relatively flexible compared to these other portions of the plate. The under side of this curved 50 tapered surface 4 is provided with a backing 5 of similar shape and of any suitable material, such as felt, whereby the proper friction is produced between the plate and the record. Ordinarily, however, as shown 55 in Fig. 6, the felt 5 is not directly in contact with the record. During the normal disposition of the plate on the record, while the needle is travelling over the outermost groove to the point where it becomes temporarily 60 disengaged from the plate, the plate

is supported and bears on the record at three points. The first two of these points, 6 and 7, are formed as dependent projections out of the material of the plate by suitably stamped portions. These dependent projecting bearing portions 6 and 7, it will be noted, are formed along the edge of the plate and will bear on those portions of the record along the margin which have no grooves 70 thenceon, so that the weight of the plate is 75 borne by those parts of the record which can well afford to receive pressure without injuring any of the grooves. Another bearing point, 8, is a felt surface formed on the lower side of the plate 9 sliding within a dove-tailed slot 10 in the broad end 11 of the plate 1, as seen particularly in Figs. 1, 3 and 5. This plate 9, which is preferably made of some light material such as aluminum, can slide back and forth in the slot 10 and 85 has a pointed end 12 (see Fig. 1) adapted to be adjusted with respect to its radial distance from the center of the record. The forward edge of the broad end of the plate is gradually curved, as shown at 13 in Fig. 1, 90 so that as the needle travels in the groove on the record this edge of the plate bears thereagainst and the needle gradually moves along the smooth curved edge 13 until it bears against the edge 12 of the plate 9. 95 When it reaches the end of this plate 9 and becomes disengaged therefrom, the natural friction between the plate and the record causes the plate to move and rotate, whereby the needle will enter the broad end of the 100 groove 3 and encounter the surface 4, which is flexible for the reasons above referred to. The surface of felt or other material formed on the lower side of the plate 9 is intended to act not as much as a bearing surface as 105 it is intended to act as a brush moving in front of the needle to clean the grooves so that the needle will not encounter dust, dirt and grit which cause discordant noises to be produced. As the needle bearing the weight 110 of the tone arm of the phonograph bears on the surface 4 it will slightly depress the same, forcing the flat portion or surface 5 down on the record to increase the friction between the plate and the record, whereby 115 the positive movement of the plate with the record, in spite of the weight of the needle and the tone arm, will be properly insured. The needle will then travel to the small narrow end of the groove and be fed on to the record in the usual manner. The forward outer end of the plate near the narrow end of the groove 3 is provided with a projecting edge 3' extending beyond the end of the groove and lying substantially parallel to the exact groove in the record into which the needle is to be fed. It will be observed from a consideration of the operation of this device that as the needle is 120 swung from the center of the record to the 125 edge 3' it will strike the edge 3' and be 130

outer edge thereof by the short sharp cam slot, there may be a tendency for the needle to jump off the record or to jump from one groove to another, and this tendency is absolutely prevented by reason of the fact that the needle, after leaving the narrow end of the groove 3, contacts with the edge 3^a which guides it into the proper groove and maintains contact with it long enough to insure that the needle will not have any additional lateral movement.

In the form of the invention shown in Figs. 1, 2 and 3, I have provided a centrally depressed portion 14 also bearing on the record and provided with two apertures 15 and 16. This depressed portion 14 is centrally located on the record and bears on that portion generally carrying the label and not provided with grooves, so that this depressed portion 14 really is the third main bearing surface for the plate, the fourth being the incidental bearing of the brush portion above mentioned. The aperture 16 is placed over the pin of the phonograph table when a large record, such as a 12-inch record, is to be used; but when a small record, such as a 10-inch record, is to be used the hole 15 is placed over the pin 17 of the table.

It will thus be seen that I have provided a light-weight plate bearing normally with as little friction as is necessary on those parts of the record which are not provided with phonographic grooves, whereby the speed of rotation of the table is affected as little as possible and yet which is provided with means affected by the movement and weight of the needle to increase the friction at the proper moment and insure rotation of the plate. I have, furthermore, provided a plate which is adapted to be used with different sizes of records. In Fig. 8 I have shown a modified form of plate in which only one hole 18 is used. This plate is smaller than the one previously mentioned and is adapted to be used in connection with very small records, such as are sold for a relatively small amount of money.

What I claim is:—

1. A repeating device for phonographs, which comprises a plate having a curved tapered groove therein, a portion of said groove being closed by material flexible relative to the remaining material of the plate, said material being adapted to receive the

needle and be depressed thereby during the travel of the needle thereover.

2. A repeating device for phonographs, which comprises a plate having a curved tapered groove therein, a portion of said groove being closed by material flexible relative to the remaining material of the plate, said material being adapted to receive the needle and be depressed thereby during the travel of the needle thereover, and a layer of material disposed on the underside of said surface to be depressed by the needle and increase the friction between the plate and the record.

3. A repeating device for phonographs, which includes a plate to be disposed on the record, said plate having three bearing points formed dependently to provide the only normal points of contact between the plate and the record and, a tapered groove, and a sheet of material in the latter portion of said groove flexible relative to the remaining material of the plate, said sheet of material being adapted to bear the weight of the sound box assembly and be depressed thereby toward the record whereby the friction between the plate and the record is increased.

4. A repeating device for phonographs, which includes a plate to be disposed on the record, said plate having three bearing points formed dependently to provide the only normal points of contact between the plate and the record, and a tapered groove, a sheet of material in the latter portion of said groove flexible relative to the remaining material of the plate, said sheet of material being adapted to bear the weight of the sound box assembly and be depressed thereby toward the record whereby the friction between the plate and the record is increased, and a layer of friction material on the underside of said sheet of material.

5. A repeater device for phonographs, which includes a plate having a curved cam slot therein, and a needle bearing surface formed across a portion of said slot, the plate on both sides and around said needle bearing surface being stiffened or reinforced so that the needle bearing surface is relatively flexible and is depressed when the weight of the needle and the tone arm are resting thereon.
